(57) **CLAIM**

The ornamental design for a food container, as shown and described.

DESCRIPTION

FIG. 1 is a left front perspective view of a food container in accordance with the present design in a closed condition; FIG. 2 is a front view of FIG. 1; FIG. 3 is a rear view of FIG. 1; FIG. 4 is a left side view of FIG. 1; FIG. 5 is a right side view of FIG. 1; FIG. 6 is a top view of FIG. 1; FIG. 7 is a bottom of FIG. 1; and, FIG. 8 is a front perspective view of the food container in accordance with the present design of FIG. 1 in an open condition.

In the drawings, the broken lines are for the purpose of illustrating portions of the clamshell packaging container that form no part of the claimed design. In FIG. 8 the broken lines also show environment that form no part of the claimed design.

1 Claim, 5 Drawing Sheets
